UNITED STATES PATENT OFFICE.

ADOLPH M. DICKLIN AND JOHN RIPPCHEN, OF STOUGHTON, WISCONSIN.

SHOCK-ABSORBING SPRING.

1,235,190.

Specification of Letters Patent. Patented July 31, 1917.

Application filed February 13, 1917. Serial No. 148,398.

To all whom it may concern:

Be it known that we, ADOLPH M. DICKLIN and JOHN RIPPCHEN, citizens of the United States, residing at Stoughton, in the county of Dane and State of Wisconsin, have invented certain new and useful Improvements in Shock-Absorbing Springs, of which the following is a specification.

This invention relates to new and useful improvements in shock absorbing spring.

The primary object of the invention is the provision of a leaf spring construction provided with auxiliary means adapted to be brought into action upon an increased load being exerted upon the device, the construction being easy and inexpensive to manufacture and possessing great strength and durability.

A further object of the device is the provision of a vehicle spring having a portion thereof serviceable in taking up additional loads as well as absorbing shocks and jars incident to traveling whereby a light load will be suitably mounted resiliently although the spring will be serviceable for use with heavy loads.

It will be understood that this form of spring is serviceable with any manner of vehicles but is especially adapted for automobiles, the same consisting in the novel combination and arrangement of parts hereinafter fully described and illustrated in the appended drawing, and in which like designating characters refer to corresponding parts throughout the several views.

Figure 1 is a side elevation of the device partly broken away,

Fig. 2 is a horizontal sectional view taken upon lines II—II of Fig. 1,

Fig. 3 is a vertical transverse sectional view through the device,

Fig. 4 is a perspective view of one of the clips employed, and

Fig. 5 is a perspective view of an end portion of one of the main leaves of the spring.

Referring more in detail to the drawing, the device is illustrated in connection with a side rail 10 of a vehicle and the axle-tree 11 thereof, the spring being interposed therebetween adapted for resiliently mounting the rail upon the axle-tree. Mounting brackets 12 are secured to the rail 10 in spaced relations, having the principal leaf 13 of the main leaves pivotally suspended therefrom by pintle bolts 14 carried by the said brackets

and over which the opposite ends of the said leaves are turned as at 15 in tubular arrangement, journaling the leaf therebetween which normally assumes a semi-circular form. One pintle 14 is suspended from its bracket 12 by a link 12'.

Two leaves 16, of substantially the same length and form as the leaf 13, are arranged in flat engagement therewith, while a relatively shorter leaf 17 is similarly positioned. Two substantially straight auxiliary leaves 18 are positioned therebeneath, being of substantially the same length as the leaf 16, while all of the aforementioned leaves are secured together centrally by a bolt 19 in the formation of a unitary leaf spring. Yoke or strap bolts 20 encircle all of the leaves of the spring and are adjustably locked through a connecting plate 21 carried by the said bolts beneath the axletree 11 and whereby the spring is secured to the axletree for service.

The lower one of the two leaves 16 has its opposite ends provided with notches 22 and the bifurcated portions 23 overturned for receiving pins 24 therethrough, while U-shaped clips 25 span the leaf 13 and the adjacent leaf 16, being provided with spaced ears 26 having journaling perforations 27 therein through which the pins 24 pass, the said pins being retained in any suitable manner. A flat link 28 is swingingly mounted upon each of the pins 24 within the aforementioned slots 22, the said links depending through alining slots 29 arranged adjacent the opposite free ends of the auxiliary leaves 18 of the spring. Stop lugs 30 of any desired form, being preferably of cylindrical arrangement, are arranged upon opposite sides of the links 28 at a point between the leaves 16 and 18, and being normally out of engagement therewith, while a similar cylindrical lug 31 is arranged upon each side of the links 28 adjacent the lower free ends thereof and beneath the auxiliary leaves 18, as clearly shown in Fig. 1.

In operation, a light load upon the rail 10 will be resiliently carried by the four main leaves 13, 16 and 17 of the spring, while any sudden jar or an increased load placed upon the rail 10 depresses the opposite ends of the main leaves bringing the lugs 30 into contact with the upper faces of the adjacent auxiliary spring 18 whereby the latter assists in supporting the load. The normal position of the members being illustrated in Fig. 1,

2

it will be also apparent that any sudden jar as well as an excessive load will bring the stops 30 into engagement with the auxiliary leaves 18 thereby relieving the main leaves 5 of the spring. Upon the return movement of the main leaves, the lower stops 31 will engage the auxiliary leaves 18, thereby cushioning as well as limiting the movement of the main leaves, both sets of lugs 30 and 10 31 serving as a shock absorbing means in connection with the auxiliary leaves 18. It will be understood that the link 12' allows the spring to lengthen during the operation of the device.

15 What I claim as new is:

1. A leaf spring construction comprising a plurality of main leaves, auxiliary leaves of different longitudinal form centrally secured to the said main leaves, and means 20 for guiding and limiting the movements of the ends of the auxiliary leaves loosely associated therewith and pivotally connected to the ends of the main leaves.

2. A spring comprising normally curved 25 main leaves, approximately straight auxiliary leaves centrally secured thereto, and limiting connections between the opposite end portions of the main and auxiliary leaves pivoted to the main leaves and loosely 30 associated with the auxiliary leaves.

3. A device of the class described comprising a plurality of main leaves, a plurality of approximately straight leaves, a connector centrally securing all the leaves 35 together, and limiting links for the auxiliary leaves carried by the main leaves, the second-named leaves remaining functionless under slight stress upon the main leaves.

4. A device of the class described comprising a plurality of main leaves, a plurality of approximately straight leaves, a connector centrally securing all the leaves together, depending links pivoted to the under surface of the main leaves, and stop lugs carried by the said links arranged adjacent 45 the opposite faces of the said auxiliary leaves.

5. A spring comprising brackets, main leaves journaled between the said brackets, auxiliary leaves centrally attached to the 50 main leaves and having slots adjacent their free ends, links pivotally depending from the main leaves and extending through the said slots, and oppositely arranged pairs of limiting stops carried by the said links at opposite sides of the auxiliary leaves.

55 6. A spring comprising flatly engaging curved main leaves, the ends of one of the lower curved main leaves being notched and looped, pins journaled through the said lower ends, U-shaped clips spanning the adjacent leaves and journaled upon the said pins, auxiliary leaves centrally secured to the said main leaves, having slots therethrough, links journaled upon the said pins 60 within the notches of the aforementioned main leaves and slidably arranged through the slotted leaves, and limiting stops upon the said links adapted for engagement with the auxiliary leaves during the operation of 70 the device.

In testimony whereof we affix our signatures.

ADOLPH M. DICKLIN.
JOHN RIPPCHEN.
